UNITED STATES PATENT OFFICE.

WILLIAM A. VOLLMER AND FRANK B. HARMAN, OF KENOSHA, WISCONSIN, ASSIGNEES
TO SIMMONS COMPANY, OF KENOSHA, WISCONSIN, A CORPORATION OF DELAWARE.

POST AND RAIL CONNECTION.

Application filed June 15, 1923. Serial No. 645,499.

Our invention relates to improvements in post and rail connections and, although susceptible of varied use is of particular service in connection with furniture constructed of sheet metal.

The principal objects of the invention are to provide a simple, neat, economical and efficient construction by which a standard may be mounted on a table top, for example, 10 a bed room dresser; to provide a construction which has the double purpose of securing a standard to a rail and of securing said rail to a table top; to provide a construction in which the parts for effecting the connection, although exteriorly adjustable, are so placed as to be substantially concealed from the ordinary view; to provide a construction particularly adaptable for use in connecting members made of straight wall 15 metal tubing; to provide a construction arranged so that the standard or post may be readily demounted for shipment and reassembled with equal facility; to provide a construction which shall be simple and economical 20 to design and manufacture, while being neat, sturdy and efficient for the purpose intended, and in general to provide an improved construction of the character referred to.

30 In the drawings which illustrate our invention as applied to a bed room dresser of simple design,

Fig. 1 is a fragmentary elevation showing the dresser top and associated mirror standards.

Fig. 2 is a section taken on the line 2—2 of Fig. 1.

Fig. 3 is a section taken on the line 3—3 of Fig. 2.

40 Fig. 4 is a section taken on the line 4—4 of Fig. 2.

Fig. 5 is a perspective view of the bottom end of one of the standards, and

Fig. 6 is a section taken on the line 6—6 of Fig. 1.

Referring to the drawings, 10 represents as a whole the dresser to which our invention is shown applied. Said dresser is constructed of sheet metal throughout and embodies a frame work of metallic tubing, one of the members of which includes a horizontally extending back rail 11 of rectangular steel tubing. The table top, which is supported by the body frame work of the dresser 50 is constructed of a steel sheet 12 supported

on a frame work of rectangular steel tubing, one member of which is indicated at 13 and partially overlies the back horizontal member 11 of the body frame work. Preferably in order to lessen the noise, paper strips as at 14 are interposed between the top sheet 12 and its supporting frame work. 60

The mirror, designated as a whole 15 is swung between a pair of posts or standards 16 and 17 each constructed of metallic tubing having a square cross section. The standards 16 and 17 are mounted on the pedestal rail 18 also constructed of rectangular steel tubing. Said rail or pedestal 18 is punched out as shown in Figs. 2 and 3 so as to admit 70 the lower end of the standard, and it will be observed that in punching out said apertures the entire top wall 19 of the pedestal rail 18 is removed for a distance equal to the exterior width of the tubing from which the standard 16 is constructed. It will also be observed that the back wall 20 of the standard 16 is telescoped within the rear wall 21 of said pedestal rail while the front wall 22 of the upper portion of the standard 16 terminates at and rests upon the front wall 23 of the rail 18, said parts 22 and 23 being in alignment.

In order to avoid the necessity of cutting away that portion of the tube 16 located inside of the tube 18 in order to permit of its insertion, we prefer to notch the front of the tube 16 as shown at 24, afterward caving in the front wall of the lower portion thereof as indicated at 25 thereby enabling 90 the said lower end to be slipped down into the pedestal rail 18. The joint between the front walls 22 and 23 of the standard and pedestal rail is concealed by the face plate 26, the lower end of which rests upon the 95 surface of the top sheet 12 while the upper end thereof extends a short distance above the said joint 27. Preferably, the face plate 26 is made with a pair of rearwardly bent lugs or extensions 28 spaced to embrace 100 closely the sides of the standard 16, the upper edges of which are aligned with the upper edge of the face plate 26, while the lower edges of said lugs 28 rest upon the top wall 19 of the pedestal rail. In order 105 to secure said face plate 27 in position, it may be brazed at its edges to the front wall 23 of the pedestal rail or the edges of the extensions 28 may be brazed to the top wall 19 of the pedestal rail. The rail 18 is held 110

down by bolts as at 29 extending through the frame members 11 and 13 and each having its head 30 located within and engaging the lower wall 31 of the pedestal rail. It will be manifest that when the nut 32 is tightened, the bolt will serve to draw the pedestal rail 18 down toward the body frame member 11, thus clamping the frame member 13, paper 14 and top sheet 12 as well as positively securing the pedestal rail to the top of the dresser. It will be noted that the security of said connection is not affected by the presence or absence of the standard 16, subsidiary means being employed to support said standard on the pedestal rail.

By reference to Fig. 2, it will be seen that the head 30 of the bolt 29 consists of a horizontally extending head member 33 made with a rear extension bent upwardly at right angles as indicated at 34, said extension 34 being of slightly less width than the interior of the standard tube 16 so that the latter may be slid down upon said extension 34. Said extension 34 is so bent as to leave a slight space between it and the back wall 21 of the pedestal rail 18, enabling the back wall 20 of the standard 16 to be telescoped down in between the said parts. One or more cap screws as at 35, passing through suitable apertures in the walls 20 and 21 of the post and rail respectively and fitting suitably tapped holes in the vertical extension 34 of the bolt head, serve to clamp the said parts 21, 20 and 34 rigidly together. Upon removing said screws 35, the standard 16 can be readily withdrawn vertically out of the pedestal rail for shipping purposes.

In Fig. 6 we have illustrated an additional center support for the pedestal rail 18. Said support comprises a small flat bar 36 extending vertically between the rail 18 and certain body framing. As shown, the upper end of said bar 36 is united to the inside of the rear wall 21 of the pedestal rail by screws as at 37. The lower wall 31 of said pedestal rail is punched out as are the top sheet 12, deadening strip 38 and table top frame member 39 in order to enable the lower end of said bar 36 to slide into a channel-like pocket formed in the back sheet 20 of the dresser body portion. Bolts as at 41 are used for clamping said bar 36 to the back of a vertically extending frame member 42 constituting a portion of the dresser body frame work.

The described details of construction being merely illustrative of one phase of our invention, it will be understood that the scope of same should be interpreted by reference to the appended claims, said claims being construed as broadly as possible, consistent with the state of the art.

We claim as our invention:

1. In furniture, the combination of a pedestal rail, a horizontally extending frame

member underlying said rail, a bolt extending through said frame member and upwardly into said rail for drawing said parts together, a standard extending downwardly into said rail, and an extension on said bolt to which said standard is secured.

2. In metal furniture, the combination of a hollow pedestal rail, a hollow horizontally extending frame member underlying said rail, a bolt extending from said frame member and upwardly into said rail for drawing said parts together, a standard extending downwardly into said rail, and an extension on said bolt detachably secured to said standard.

3. In metal furniture, the combination of a hollow pedestal rail, a hollow horizontally extending frame member underlying said rail, a bolt extending from said frame member and upwardly into said rail for drawing said parts together, a standard extending downwardly into said rail, and an extension on said bolt detachably secured to said standard and telescoped within said standard.

4. In sheet metal furniture, the combination of a pedestal rail constructed of metal tubing, a horizontally extending frame member underlying said rail and also constructed of metal tubing, a bolt extending through said frame member and upwardly into said rail for drawing said parts together, a hollow standard constructed of metal tubing and extending downwardly into said rail and an extension on said bolt inside of said standard and to which said standard is clamped.

5. In sheet metal furniture, the combination of a pedestal rail constructed of metal tubing, a horizontally extending frame member underlying said rail and also constructed of metal tubing, a bolt extending through said frame member and upwardly into said rail for drawing said parts together, a hollow standard constructed of metal tubing and extending downwardly into said rail and an upward extension on said bolt inside of the standard and to which said standard and rail are clamped, said clamping means comprising screws inserted through walls of said rail and standard and threaded into said extension.

6. In metal furniture, the combination of a hollow pedestal rail, a hollow horizontally extending frame member underlying said rail, a bolt extending from said frame member and upwardly into said rail for drawing said parts together, a standard extending downwardly into said rail, an extension on said bolt detachably secured to said standard and a face plate concealing the point of entrance of said standard into said rail and having lugs extending rearwardly at its upper end and embracing said standard.

7. In metal furniture, the combination of

a hollow pedestal rail, a hollow horizontally extending frame member underlying said rail, a table top interposed between said rail and said member, a bolt extending through 5 said frame member and upwardly into said rail for drawing said rail, said top and said member together, a standard extending downwardly into said rail, and an extension 10 on said bolt to which said standard is secured.

8. In metal furniture, the combination of

a hollow pedestal rail, a hollow horizontally extending frame member underlying said rail, a table top extending between said rail and said member, a bolt extending through 15 said frame member and said top and upwardly into said rail for drawing said parts together, and a standard detachably secured to said rail.
